(57) **CLAIM**

The ornamental design for a measuring instrument, as shown
and described.

DESCRIPTION

FIG. 1 is lower perspective view of the measuring instrument
of my new design;

FIG. 2 is a top plan view of the measuring instrument of my
new design;

FIG. 3 is a bottom plan view of the measuring instrument of
my new design;

FIG. 4 is a left side view of the measuring instrument of my
new design;

FIG. 5 is a right side view of the measuring instrument of my
new design;

FIG. 6 is a front end view of the measuring instrument of my
new design; and,

FIG. 7 is a rear end view of the measuring instrument of my
new design.

The broken line showing of structural features is included for
the purpose of illustrating non-claimed subject matter and
forms no part of the claimed design.
